O. B. PULIS

ROAD RAIL

Filed Feb. 15. 1922

UNITED STATES PATENT OFFICE.

OSCAR B. PULIS, OF MILWAUKEE, WISCONSIN, ASSIGNOR TO METAL FORMS CORPORATION, OF MILWAUKEE, WISCONSIN, A CORPORATION.

ROAD RAIL.

Application filed February 15, 1922. Serial No. 336,705.

To all whom it may concern:

Be it known that I, OSCAR B. PULIS, citizen of the United States, residing at Milwaukee, in the county of Milwaukee and State of Wisconsin, have invented certain new and useful Improvements in Road Rails, of which the following is a specification.

The present invention relates to improvements in the design and construction of that type of metal forms which are employed when constructing roads, pavements, curbing or the like, from concrete or other plastic material, and among the objects of the invention is to provide a device of this character which has great sturdiness and rigidity and will successfully withstand rough usage and heavy superimposed loads.

These forms or rails are used very extensively in the construction of concrete roads, and there is a constantly growing tendency to utilize the rail forms for the support of various kinds of machines and mechanisms, as examples of which subgrade planers and concrete finishing machines may be mentioned. Under such conditions the heads of the rail forms are subjected to the battering action and impact of the wheels or runners upon which the mechanism is mounted, as well as to the additional weight of the superimposed load. A strong and rigid construction is necessary to avoid bending or buckling of the rail and to prevent the head of the rail from being distorted and bent out of shape.

The present construction of road rail has been designed to meet these conditions of service, and has a tubular body formation which gives the rail itself great strength and rigidity, together with a head which is formed of a plurality of thicknesses of material so that it will be able to withstand the battering action of any machinery or mechanism which may be mounted thereon without danger of becoming distorted.

With the foregoing and other objects in view, the invention consists in certain combinations, formations and associations of the parts, as will more fully appear as the description proceeds, the novel features

thereof being pointed out in the appended claims.

In connection with the following description reference is to be had to the accompanying drawings, in which:—

Figure 1 is a perspective view of one end of a road rail which is constructed in accordance with the invention.

Figure 2 is a transverse sectional view through the same.

Figure 3 is a transverse sectional view through a modified form of the road rail.

Figure 4 is a similar view showing a still further modification.

Corresponding and like parts are referred to in the following description and indicated in all of the views of the drawing by like reference characters.

Referring to Figures 1 and 2 of the drawing, which illustrate one of many possible embodiments of the invention, the numeral 1 designates the base of the road rail or form, said base being of a considerable width so as to obtain an extended bearing surface and provide a solid support for the rail. The base is formed of sheet metal of a suitable thickness or gauge and one edge thereof is bent upwardly to provide the face 2 which may be of any desired height, depending upon the thickness of the concrete to be deposited or upon the character of the work to be performed. At the upper edge of the face 2 the sheet metal is bent laterally to provide the head 3, and a depending lip 4 may be provided at the free edge of the head.

The foregoing parts are all formed from one piece of sheet metal, and associated therewith is an inclined web or back member 5 which is formed of a second piece of sheet metal. This back member constitutes a brace between the base 1 and the face and head of the rail. As shown by Figures 1 and 2 of the drawing the bracing web 5 is inclined and extends substantially between the rear edge of the base 1 and the angular intersection of the face 2 and head 3. Being inclined the web 5 has no tendency to retain thereon particles of plastic material; in fact the web forms a shed for

concrete dropping thereon. The lower edge of the reinforcing web 5 is formed with a flange 6 which rests upon the base 1 at a point adjacent to the edge thereof, being 5 permanently and rigidly connected thereto in any suitable or approved manner as by means of the spot welding 7. The upper edge of the reinforcing web 5 is bent outwardly to provide thicknesses 8 and 9 which 10 fit against the inner faces of the head 3 and lip 4, respectively, being fastened thereto in some suitable manner as by means of the spot welding 10.

With this construction it will be noted 15 that the body of the rail has a tubular formation which gives it great inherent strength and rigidity so that the rail can support heavy loads and withstand severe usage without danger of bending or buckling. Furthermore the head of the rail is 20 formed of a plurality of superimposed thicknesses of material so that it will not be bent out of shape or distorted by the battering action of any rolling stock or machinery of any kind which may be mounted 25 to travel thereon. The depending lip or flange at the free edge of the head also tends to give the head increased strength, since the head is practically in the form of 30 an inverted channel member and is reinforced at both of its longitudinal edges by depending flanges or the equivalents thereof.

The forms or rails may be supported in 35 position by means of the usual stakes 11, and these stakes are shown as being inserted through vertically aligned openings in the base 1 and inclined reinforcing web 5. Wedge members 12 may be utilized to 40 hold the rail in any position on the stake, to allow blocking or wedging under the base where the sub-soil has not been perfectly graded. The wedge members are illustrated as extending through slots 13 in the 45 reinforcing webs 5 and engaging keepers 14 upon the base 1. The outer ends of the wedge members may be bent at an angle to provide a head or lip 15, and it will be 50 obvious that when the wedge members are driven into position the edges thereof will be caused to grip the sides of the stakes 11 and to lock the road rails in position upon the stakes. The form and arrangement of the stake locking means is not really 55 essential to the invention and can be changed or modified as may be desired. It is notable that the wedges 12, however, are practically entirely housed by the hollow portion of the form, this being of especial advantage in a concrete form.

A modification is shown by Figure 3 in which the reinforcing element or web 5^a is arranged in a slightly different manner and extends from the outer edge portion of

the base 1 to the outer edge portion of the 65 head 3. The lower edge of the reinforcing element is secured, as in the previous instance, to the base plate, and the upper edge thereto has a short vertical portion 5^b which engages the interior of the lip 4, 70 and an inward extension 8^a, which extends under the head 3 and is secured thereto. This design also provides a tubular body portion for the rail which has great inherent strength and rigidity, as well as a 75 head portion which is composed of a plurality of superimposed thicknesses of material. The tubular formation of the body has the additional advantage of preventing concrete or foreign material from lodging 80 within the interior of the rail, and interfering with the efficient use thereof. Any suitable form of stake mounting such as that illustrated by Figure 1 may be utilized in connection with the modification, as 85 shown by Figure 3.

A further slight modification is illustrated by Figure 4, in which the reinforcing web has a lower portion 5^c which is disposed at a sharper angle than an upper portion 5^d, the sharper angle of the lower portion being perhaps of advantage in providing in a slightly better manner for the stake 11, and enabling a shorter stake to be used. The upper portion 5^d of the reinforcing web engages the lip 4 of the rail head and is formed with an extension 8^c which extends under the head 3 and is permanently and rigidly connected thereto in some suitable manner as by means of spot 100 welding.

All of the different forms of the road rail have great inherent strength and rigidity so that they will not bend or buckle, and are practically indestructible so that they can 105 be used repeatedly and form in effect permanent equipment for the contractor or road builder using the same. Furthermore, the road rails are inexpensively formed of sheet metal and have a simple construction. 110

For the purposes of illustration three different embodiments of the invention have been illustrated and described in detail, although it will be understood that I do not restrict myself to these specific forms of the 115 invention, since it is obvious that in any modifications changes can be made in the details of the construction without departing from the spirit of the invention.

Having thus described my invention, what 120 I claim as new and desire to secure by Letters Patent is:—

1. As a new article of manufacture, a unitary road form and rail structure, the same comprising a base extended upwardly 125 at one edge to provide a form face, and thence extended laterally to provide a head, and a web joined to the base at its other

- edge and inclining upwardly and inwardly to engage beneath the head, said head and web being interlocked at their engaging portions.
5. 2. A unitary road rail structure of the character described, which is constructed of sheet metal and has a head portion, the sheet metal being overlapped at the head portion to provide a plurality of thicknesses of material.
10. 3. A unitary road rail structure of the character described, which has a tubular body portion and is formed with a head, said rail being constructed of sheet metal which is overlapped at the head portion to provide a plurality of thicknesses of material.
15. 4. A road rail of the character described, which is formed of sheet metal and includes a base, front and head, in combination with a reinforcing back web, said web having an extension which laps and interlocks with the head portion of the rail to provide a plurality of thicknesses of material at the said head portion.
20. 5. A road rail of the character described, which is formed of sheet metal and includes a base, front and head portion, in combination with an inclined reinforcing web at the back thereof, the inclined web and base having corresponding stake receiving openings formed therein and the web being formed with an extension which fits against the head portion of the rail to provide a plurality of superposed thicknesses of material at the said head portion.
25. 6. A road rail of the character described, which is formed of sheet metal and includes a base and front member in combination with an inclined stiffening web co-extensive with the longitudinal area of the base and front member, the base and inclined web having corresponding stake receiving openings formed therein.
30. 7. A road rail of the character described, including a base member, front portion and head which are formed of one piece of sheet metal, in combination with a reinforcing web which is formed of a complementary piece of sheet metal, said reinforcing web being formed with an extension which extends along and fits against the head portion of the rail to provide a double thickness of sheet metal at the said head portion.
35. 8. A road rail of the character described, including a base, front portion and head which are formed of one piece of sheet metal, the head having a depending lip at the free edge thereof, and an inclined reinforcing web which is formed of a complementary piece of sheet metal and extends between the front portion of the rail and the rear edge of the base, the upper edge of the reinforcing web being formed with an ex-
- tension which fits against the head and lip at the edge of the head, thereby providing two superposed thicknesses of material at the said head portion and lip.
9. A road rail of the character described, including a base, front portion, head, and a rear reinforcing web co-extensive with the said base and front portion, the said members being formed of sheet metal and edge portions of the sheet metal being caused to overlap at the head to provide two superposed thicknesses of material at this point.
10. A road rail of the character described, having a hollow formation, in combination with a supporting stake a portion of which extends into the interior of the hollow rail, and locking means arranged within the interior of the rail and operable from the outside thereof for clamping the rail in position on the stake.
15. 11. A road rail of the character described, having a hollow body portion, a supporting stake of which a portion normally projects into the interior of the rail, and a locking wedge member entering the rail and operable from the exterior thereof for locking the rail in position upon the stake.
20. 12. A road rail of the character described, including a tubular body portion formed of sheet metal and having a horizontal base and inclined brace member arranged above the base, a vertically disposed supporting stake extending loosely through the base and inclined brace member, a keeper on the base, and a wedge member passing through a side opening in the rail and engaging the keeper so that it is operable from the exterior of the rail and is adapted to engage the stake to lock the rail in position thereon.
25. 13. As a new article of manufacture, a unitary road form and rail structure, the same comprising a base extended upwardly at one edge to provide a form face, and thence extended laterally to provide a head, and a web joined to the base at its other edge and inclining upwardly and inwardly to engage beneath the head, said head and web being interlocked at their engaging portions, the said web being continuous throughout the length of the base and head portions of the structure.
30. 14. As a new article of manufacture, a unitary road form and rail structure, the same comprising a base extended upwardly at one edge to provide a form face, and thence extended laterally to provide a head, a web joined to the base at its other edge and inclining upwardly and inwardly to the head, the web aforesaid extending along the base and head structure throughout the length of the rail, whereby a hollow rail body is constituted, and a stake locking device received and substantially entirely housed within said hollow body, one end of

the said locking device extending to a point exterior to the structure, whereby it may be operated.

15. A unitary road rail and form structure, comprising a base having one edge upturned to provide a form face and thence extended laterally to provide a head portion and thence downwardly to provide a lip on said portion, and a web co-extensive in

length with the said base, face, and head ¹⁰ portions, and provided at its upper edge with an extension interlocked with the head between the form face and said lip, and means connecting the lower edge of the web with the other edge of the base.

In testimony whereof I affix my signature.

OSCAR B. PULIS.
